UNITED STATES PATENT OFFICE.

POLK MADERSON HIGGINS AND LEE DOLPHIA HARMES, OF HOUSTON, TEXAS.

STREET OR STATION INDICATOR.

No. 876,803.

Specification of Letters Patent.

Patented Jan. 14, 1908.

Application filed October 1, 1906. Serial No. 337,016.

To all whom it may concern:

Be it known that we, POLK MADERSON HIGGINS and LEE DOLPHIA HARMES, citizens of the United States, residing at Houston, in the county of Harris and State of Texas, have invented certain new and useful Improvements in Street or Station Indicators, of which the following is a specification.

Our invention relates to indicators for displaying to passengers in a car the names of approaching streets or stations, and more particularly to indicators for trolley-cars or electrically-propelled vehicles wherein the indicator mechanism is automatically actuated at the desired points on the line or route by the temporary energizing of an electro-magnet. The main object is to provide an indicator of simple and practicable mechanism and efficient operation.

20 An exemplification of the invention is illustrated in the accompanying drawings, which are to be taken as a part of this specification. Without essentially restricting ourselves to the specific construction shown, the invention will hereinafter be fully described by reference to said drawings, and then more particularly pointed out in the appended claims.

In said drawings: Figure 1 is a side view 30 of the apparatus, with a side of the casing broken away to reveal the interior mechanism. Fig. 2 is a front view of the apparatus, with a portion of the casing broken away to show the mechanism. Fig. 3 is an enlarged 35 front view of the supply-spool C and mechanism for rewinding the tape, the surrounding casing being shown in section. Fig. 4 is an enlarged side view of a portion of the mechanism. Fig. 5 is a detail diagrammatic 40 view of a trolley-line connection for automatically energizing the controlling magnet.

As shown in the drawings, the mechanism of the apparatus is inclosed by a suitable case or cover denoted by the lever A. The 45 apparatus is intended to be mounted in the front of a car, or on the inside of the front wall of the car, and the names of the different streets or stations, printed upon a tape or strip B, are successively displayed through 50 an opening a in the front of the case. In operation, said tape B, wound upon a supply-spool C, unwinds therefrom step-by-step or intermittently and passes said opening a and winds onto a take-up drum D; the ends of 55 said tape being respectively fastened to the perimeters of said spool and drum. Both

drums C and D are arranged between the side-members of an appropriate supporting frame E, the axles or spindles of said drums being journaled or mounted on said side-members.

The drum D is actuated to wind the tape thereonto by movement of a lever F, carrying a pivoted dog or pawl G which engages the external toothed or notched rim of a ratchet or ratchet-wheel H, the latter being shown attached to the side of the drum. Said pawl G, pivoted to said lever at g, is yieldingly held in engagement with the ratchet-wheel by a spring g'; and movement of said pawl away from the ratchet-wheel is limited by a stop g'', the latter being also carried by the lever F. Said lever F is pivotally attached at f to the frame E, and is normally held by a spring f' against a fixed stop or 75 abutment f'', which latter may be a stud or projection on the frame E. In this normal position of the lever (indicated by dotted lines in Fig. 4) the pawl G is in engagement with one of the external notches or teeth of the ratchet, and by a single motion of the lever (from the dotted line position to the full line position indicated in Fig. 4) the ratchet-wheel will be turned thereby for a distance corresponding to the interval between 80 two adjacent ratchet-teeth or notches. Further motion of the ratchet-wheel is limited by means of a detent J engaging the inside rim of the ratchet-wheel, the inside teeth or notches thereof being spaced similarly but facing oppositely to the outside teeth or notches. Said detent J is shown pivoted at j to the frame E, and is normally held out of engagement with the ratchet-wheel by a spring j', but at each advance or positive movement of 85 the lever F a lug or projection j'' on said lever engages a roller j''' on said detent and thereby forces the latter into engagement with the ratchet. It will thus be seen that the detent J will prevent the drum D from turning 90 more than one step under the impulse or motion imparted by the lever F, although said detent will not interfere with the step-by-step turn of the drum since it is withdrawn from the ratchet-wheel by its spring j' as 95 soon as the lever F makes a reverse movement or returns to the position indicated by dotted lines in Fig. 4.

At the desired periods for operating the indicator, the lever F is automatically actuated 110 by means of an electro-magnet K, which becomes temporarily energized. Said magnet,

acting on the soft iron or armature f^3 of said lever, draws the lever thereto or against the end of the core k of the magnet; but as soon as the magnet becomes demagnetized, 5 said lever instantly returns, under force of its spring f' , to its normal position against the stop f^2 . The magnet K is shown mounted on the side of the frame E . For energizing said magnet, circuit-wires k' and k^2 lead 10 therefrom and constitute parts of a normally-open electrical circuit, which becomes automatically closed temporarily at the desired points on the line or route where it is desired to display the name of the coming street or 15 station. In this connection, where the apparatus is in use on a trolley-car, the said wires k' and k^2 may lead to a transformer, and thence one wire may be in electrical connection with the wheel of the car which 20 comes in contact with the ground, while the other wire may be in electrical connection with a suitable attachment on the trolley adapted to intermittently contact with the trolley-wire or with the feed-wire or with a 25 branch from the trolley-wire, at the point on the line where the indicator should be operated. For example, said wire may be carried through the trolley-pole and connect with a miniature or auxiliary trolley, the latter being supported by but normally insulated 30 from the main trolley; and such miniature or auxiliary trolley may contact with an extension or branch from the main trolley-wire, such branches being provided at proper 35 places on the line or route to operate the indicator. This contrivance is diagrammatically represented in Fig. 5, where L indicates the main trolley-wire, and l a short branch extension therefrom; and M is the main trolley 40 contacting with the wire L and carrying the auxiliary trolley N which contacts with the extension l . The branch connection from the main trolley-wire need be only of such length as to obtain a sufficient amount 45 of power for the draw-magnet to draw the lever thereto and then release the lever, since this motion will actuate the apparatus to the extent of moving the tape one step and thereby displaying the name of the coming street 50 or station.

In order to attract the attention of the passengers when the coming street is indicated, the mechanism desirably actuates a gong or bell. For this purpose, a gong or bell O is 55 shown supported by an extension or arm of the frame E , said bell being in position to be struck by a hammer or head o at the end of the lever F when the latter is retracted to its normal position.

60 From the foregoing, it will be observed that the operation is as follows: As the car approaches a street or station, the magnet K is automatically energized by the means or instrumentality provided for that purpose, 65 thereby drawing the lever F from its normal

position and causing the pawl G to turn the ratchet-wheel H one step, movement of the ratchet being limited by the detent J . Thus the drum D is moved one step, whereby the tape B is moved to display the name of the coming street or station through the opening a in the case. As soon as the magnet becomes demagnetized, the lever F returns to its normal position, carrying the dog or pawl G back to engagement with the next notch 70 of the ratchet-wheel, ready for the next operation; the detent J being released from the ratchet by the withdrawal of the lever, and the gong O being sounded as the lever retracts. Thus each operation is effected by 75 the temporary energizing of the magnet. 80

Provision is made for rewinding the tape onto the spool C when the circuit of the car is ended, and the car starts over the route a second time. For this purpose, the axle of 85 the spool C is shown provided with a pinion c in mesh with a gear c' , the latter having a stub-shaft c^2 adapted to be interlocked or engaged by the shaft p of a detachable crank P . In attaching the crank P on said stub-shaft, a flange p^1 carried by said crank bears 90 upon a lever Q and thereby pulls a cord or string q which is guided through suitable eyes q' on the frame E and lever F to the back of the pawl G , being attached to the latter at q^2 , so that the effect of attaching the 95 crank P to rewind the tape is to disconnect the pawl G from the ratchet-wheel H and allow the tape to be rewound. After 100 rewinding, the crank P is taken off, and the indicator is ready for another circuit.

We claim as our invention and desire to secure by Letters Patent of the United States:

1. A street or station indicator for cars 105 comprising, in combination, a case having a display-opening, a tape bearing the names of streets or stations which are successively displayed therethrough, a supply-spool and a take-up drum in said case, the tape adapted 110 to wind onto said drum from said spool, a ratchet-wheel on said drum, a lever arranged beside said drum and carrying a spring-actuated pawl engaging said ratchet-wheel, said lever being spring-held in normal position, and an electro-magnet mounted beside 115 said drum and adapted to be temporarily energized for operating said lever to effect an intermittent motion of said drum, the lever being drawn by said magnet when energized, means for rewinding the tape onto 120 said spool from said drum, and means controlled by the rewinding instrumentality for withdrawing said pawl from said ratchet-wheel.

2. A street or station indicator for cars comprising, in combination, a case having a display-opening, a tape bearing the names of streets or stations which are successively displayed therethrough, a supply-spool and 125

a take-up drum in said case, the tape adapted to wind onto said drum from said spool, a ratchet-wheel on said drum, a lever arranged beside said drum and carrying a spring-actuated pawl engaging said ratchet-wheel, said lever being spring-held in normal position, and an electro-magnet mounted beside said drum and adapted to be temporarily energized for operating said lever to effect an intermittent motion of said drum, the lever being drawn by said magnet when energized, a detachable crank for operating said spool to rewind said tape thereon, said crank having a flange, and a lever and a cord connecting said lever with said pawl, said lever adapted to be engaged by said flange when said crank is applied and thereby operated to pull said cord and disengage said pawl from said ratchet-wheel.

20 3. In a street or station indicator for cars, the combination with a name-bearing medium adapted to be intermittently moved

for successively displaying the names thereon, of an actuating mechanism therefor comprising a ratchet-wheel having internal and external teeth or notches oppositely faced, a lever mounted beside said ratchet-wheel carrying a spring-actuated pawl engaging said ratchet-wheel on one rim, means holding said lever in normal position, an electro-magnet adapted to be temporarily energized for drawing said lever thereto, whereby an operation of said ratchet-wheel is effected, a spring-retracted detent normally out of engagement with but adapted to engage the other rim of said ratchet-wheel, and means whereby said detent is moved into engagement with said ratchet-wheel by said lever when drawn by said magnet.
